Inventor
Daniel N. Wilkerson
By Attorney

UNITED STATES PATENT OFFICE.

DANIEL N. WILKERSON, OF WASHINGTON, DISTRICT OF COLUMBIA.

CLOTHESLINE.

Application filed August 17, 1922, Serial No. 582,437. Renewed May 11, 1925.

To all whom it may concern:

Be it known that DANIEL N. WILKERSON, a citizen of the United States, residing at Washington, District of Columbia, has invented certain new and useful Improvements in Clotheslines, of which the following is a specification.

This invention relates to an improvement in pinless clothes lines and has special reference to a link for pinless clothes lines made of a single length of wire and having clothes receiving eyes and a spiral twisted spring clamp for holding the clothes, said link having one portion constituting a strain receiving bar.

More particularly the invention relates to an improvement on the patent issued to William P. Henderson, October 22, 1912 and bearing the Number 1,042,345.

In carrying out the invention forming the subject matter of the above mentioned application into practical use it has been found that there is great difficulty in maintaining a direct lineal pull on the strain bar portion of the device because the clothes receiving eye at the end is apt to become deformed through continuous use and the stress exerted by the link to which that eye is connected is apt to be brought out of alignment with the strain bar by the eye in the end of that link slipping up away from such strain bar. In consequence, a pull is exerted which draws the wrapping at the opposite end along the strain bar and thus frees the loop, or eye, at the terminal of such opposite end so that it will open and the clothes line links will separate at this point. This is especially true when a heavy weight, such as wet blankets, bed spreads, and the like, is brought thereon. In order to overcome these objections which have been found by practical use of the device, I have improved the same and the principal object of the improvement is to ensure that the strain comes directly on the strain bar and cannot come on the spring clamp as in the prior patent.

With this object in view, the invention consists in general of an improved construction of clothes line link having a straight strain receiving bar extending from one end to the other end also having a portion of the wire forming the link spirally twisted about the middle of the strain receiving bar and

bent to provide clothes receiving eyes at its ends, together with means for maintaining stresses exerted on the link in substantial alignment with the strain receiving bar at all times.

In the accompanying drawings, like characters of reference indicate like parts in the several views, and:

Figure 1 represents a portion of a clothes line constructed of a plurality of these links.

Figure 2 is an enlarged detail side view of one of the links.

Figure 3 is a plan view of this link.

Figures 4 to 8, inclusive, are modifications of the link and showing the means employed for maintaining the strain in axial alignment with the strain bar.

In the embodiment of the invention it will be seen that from the figures, each link consists of a single length of wire having a straight portion 10 constituting the strain bar. One end of this strain portion is doubled upon itself as at 11 to form an eye for the attachment of the next succeeding link. At the other end of the straight portion the wire is doubled back as at 12 in Figure 2 to form a loop engaging this eye in the adjacent link. From this point the wire is curved away from the strain bar and back towards it as at 13 to constitute a clothes receiving eye, the wire being then wrapped with one or more turns around the strain bar and extending toward the eye 11. This end of the wire is then wrapped in a tight coil about the rebent portion at the other end and about the strain bar so as to constitute a wrapping 14 which holds the eye 11 from opening. With the device as thus constructed it will be seen that the rebent portion or loop 12 of one link being engaged by the rebent portion or eye 11 of the next link, the strain on the bar 10 is substantially in line therewith and no strain is brought by the tension of the links on the twists 15. Thus there is no tendency for the wrap 14 to move off of the rebent portion 11 in the direction of the loop 13. It is to be noticed that near the wrapping 14 a second eye 16 similar to the eye 13 is formed and that this second eye lies at the right angles to the eye 13. In the form shown in Figure 4 the backwardly bent portion 12 is modified by forming the same in a triangular manner as at 17. In the form

shown in Figure 5, the backwardly bent portion 12 is again modified to form a small eye 18. In Figure 6 the modification is made by bending the wire back to form an eye 18 and then tying it around the bar 10 as at 19. In Figure 7, the end is modified by bending the wire around to form an eye 20 and wrapping it once about the bar 10 as at 21. Figure 8 shows a slight modification 10 of the form of eye shown in Figure 5. In each of these instances it will be seen that there is an eye at each end of the strain bar which is distinct in its function from the clothes receiving eyes at the ends of the 15 spirally twisted portions.

There has thus been provided a simple device of this description which is an improvement of the device previously referred to by reason of the provision of a 20 straight strain bar in each link with eyes at each end for interlocking with the adjacent link.

Having thus described the invention what is claimed as new, is:—

A pinless clothes line link made of a 25 single length of wire having a portion constituting the strain receiving bar straight throughout its length, said portion being bent at each end to provide an eye for connection to adjacent links, the wire being 30 continued from one end by a sharp bend from the eye at said end to provide a clothes receiving eye adjacent that end and to be then wrapped spirally about the strain bar portion and diverging therefrom, said wire 35 being then directed toward the strain bar and being tightly wrapped about the remaining eye, said diverging portion and the portion directed toward the strain bar constituting one side of a clothes receiving eye. 40

In testimony whereof I affix my signature.

DANIEL N. WILKERSON.
